CLAIM

The ornamental design for a changing table as shown and described.

DESCRIPTION

FIG. 1 is a top perspective view of a changing table showing my new design;

FIG. 2 is a rear perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion labeled as “9” on FIG. 1;

FIG. 10 is an enlarged view of a portion labeled as “10” on FIG. 1;

FIG. 11 is an enlarged view of a portion labeled as “11” on FIG. 2;

FIG. 12 is an enlarged view of a portion labeled as “12” on FIG. 2;

FIG. 13 is an enlarged view of a portion labeled as “13” on FIG. 2; and,

FIG. 14 is an enlarged view of a portion labeled as “14” on FIG. 2.

The long dash-short dash broken lines depict enlargement boundaries that form no part of the claim. The evenly-spaced broken lines illustrate portions of the changing table that form no part of the claimed design.

1 Claim, 14 Drawing Sheets
